JACOB C. LARSEN AND GEORGE T. JOHNSON, OF COLUMBUS, OHIO, ASSIGNEES TO THE BUCKEYE STEEL CASTINGS COMPANY, OF COLUMBUS, OHIO.

SIX-WHEEL-TRUCK CONSTRUCTION FOR RAILWAY-CARS.

1,253,842.

Specification of Letters Patent. Patented Jan. 15, 1918.

Application filed October 12, 1917. Serial No. 196,165.

To all whom it may concern:

Be it known that we, JACOB C. LARSEN, a subject of the King of Denmark, and GEORGE T. JOHNSON, a citizen of the United States, and residents of Columbus, in the county of Franklin and State of Ohio, have invented certain new and useful Improvements in Six-Wheel-Truck Constructions for Railway-Cars; and we do hereby declare the following to be a full, clear, and exact description of the invention, such as will enable others skilled in the art to which it appertains to make and use the same.

This invention relates to an improvement in six wheel truck construction for railway cars.

The object of the invention is to provide a system of separate bolster units which will transmit both the side and center bearing loads properly to the truck frame, and also a construction which will permit of the easy removal and replacement of the center axle and its wheels.

With these and other objects in view, the invention consists in auxiliary bolsters extending transversely of the truck, a longitudinal bolster at each side of the truck and supported by the transverse bolsters and a main center bolster supported adjacent its ends by the longitudinal bolsters.

The invention further consists in the parts and combination of parts as will be more fully described and pointed out in the claims.

In the accompanying drawings; Figure 1 is a view in plan of our improvement, showing the ends of the truck side frames broken away; Fig. 2 is a side view, one half being in elevation and the other half in section through one of the longitudinal bolsters; Fig. 3 is a view in section on the line 3—3 of Fig. 1; Fig. 4 is a similar view on the line 4—4 of Fig. 1; Figs. 5 and 6 are views in section of two forms of side bearings on the longitudinal bolster, and Fig. 7 is a similar sectional view as Fig. 3, showing side bearings located on the extension of the center bolster.

The invention is applicable for use with any six wheel truck, and while we have illustrated one form of side frame in connection with our improvement, we have done so for the purpose of illustration only, and not with the intention of limiting our invention

to such, or any other particular construction 55 of side frame.

7 represents the truck side frames, there being two to each side with their adjacent ends overlapping, as shown in Fig. 1 for the connection therewith of the frames 8 carrying the bearing for the center axle 9. Each side frame 7 has a bearing for a journal of an end axle 10, and each is also provided with an opening 11 for the reception of one end of a transverse or auxiliary bolster 12, each bolster 12 being yieldingly supported adjacent its ends, on springs 13 seated within said openings 11. The transverse bolsters 12 are located as shown, one between the front and middle axles, and the other between rear and middle axles, and each is provided with two openings 14, shown in Figs. 2 and 4, for the reception of the ends of the longitudinal bolster 15, each of the latter being supported at its ends by 75 the transverse bolsters 12.

The main bolster 16 is, in the present instance, located over the central axle 7, and is supported at its opposite ends in openings 20 in the two longitudinal bolsters 15. Its 80 ends have suitable faces 17 and 18 (see Fig. 3) the lower faces 18 having lugs 19, preferably integral, which interlock with the longitudinal bolster 15 and which serve to hold it against endwise displacement and also 85 serve to lock the longitudinal bolster 15 against longitudinal displacement. With this construction the weight of the center bolster and its load will be sufficient to retain the bolsters in position without any 90 further securing devices other than the lugs 19, which lugs are also shown on the longitudinal bolsters.

While the main bolster may rest at its ends on the top surface of the longitudinal 95 bolster, we prefer to mount it in openings formed in the longitudinal bolsters as explained, primarily to conserve space and bring and retain the bolsters into proper relation with each other, and secondly to provide convenient shimming places where shims of varying thicknesses may be inserted in order to compensate for misfits due to inequalities in the castings, and for wear on parts affecting the center bearing 105 height.

Again in high capacity trucks, the brake rigging constitutes a very important ele-

ment, and requires considerable space for its proper accommodation. We provide for this space by using longitudinal bolsters which transmit both the side bearing loads and the main center bolster load through the transverse bolsters to the side frame.

The top members of the longitudinal bolsters, may, as shown in Fig. 1, be constructed with flat surfaces for the accommodation of separate side bearing housings such as are used with the various types of anti-friction side bearings, or as shown in Fig. 5, the longitudinal bolsters may be cast with integral side bearings 21, or, as shown in Fig. 6, with pockets 22 to receive removable side bearing blocks.

The main or central bolster 16 must be designed especially for heavy loads, and in order to possess the required strength it must have sufficient depth at its central portion. To provide for this necessary depth, without raising the center bearing, and without introducing features which would interfere with the easy removal of the middle axle, we have left the bottom of the bolster open as shown in Fig. 3 so as to permit of the free passage and movement of the middle axle.

To suit varying conditions the side bearings, instead of being secured to the longitudinal bolsters, may be located as shown in Fig. 7, in which case the main center bolster is extended beyond the longitudinal bolsters, forming short cantaliver supports for the side bearings.

It is evident that many slight changes might be resorted to in the relative arrangement of parts shown and described without departing from the spirit and scope of our invention. Hence we would have it understood that we do not wish to confine ourselves to the exact construction and arrangement of parts shown and described, but

Having fully described our invention what we claim as new and desire to secure by Letters-Patent, is:—

1. In a six wheel truck, the combination of auxiliary bolsters extending transversely of the truck, a longitudinal bolster at each side of the truck supported by the transverse bolsters, and a main center bolster separate from the longitudinal bolsters and supported at its ends by the latter.

2. In a six wheel truck, the combination of auxiliary bolsters extending transversely of the truck, a longitudinal bolster at each side and supported by the auxiliary bolsters, the said longitudinal bolsters providing supports for the side bearings, and a main center bolster separate from the longitudinal bolsters and supported by the latter.

3. In a six wheel truck, the combination of auxiliary bolsters extending transversely of the truck, a longitudinal bolster at each side of the truck and supported by the auxiliary bolster, and a main bolster carried by the longitudinal bolsters and provided with lugs which engage the latter for holding the main bolster in place.

4. In a six wheel truck, the combination of auxiliary bolsters extending transversely of the truck, a longitudinal bolster at each side of the truck and supported by the auxiliary bolsters, each longitudinal bolster having an opening through same, and a main bolster, seated adjacent its ends in the openings in the longitudinal bolsters.

5. In a six wheel truck, the combination of auxiliary bolsters extending transversely of the truck, a longitudinal bolster at each side of the truck and supported by the auxiliary bolsters, each longitudinal bolster having an opening through the same, and a main bolster seated adjacent its ends in the openings in the longitudinal bolsters and provided with lugs which engage the longitudinal bolsters for preventing displacement of the parts.

6. In a six wheel truck, the combination of transverse bolsters, longitudinal bolsters carried by the latter and a main bolster separate from the longitudinal bolsters and supported by the latter, the said main bolster having an open bottom to permit of the passage and movement of the middle axle.

7. In a six wheel truck, the combination of transverse bolsters each having two openings through the same, longitudinal bolsters supported adjacent their ends in said openings, and each longitudinal bolster having a central opening, and a main bolster supported adjacent its ends in said openings in the longitudinal bolsters.

8. In a six wheel truck, the combination of transverse bolsters each having two openings through the same, longitudinal bolsters supported adjacent their ends in said openings, each longitudinal bolster having a central opening, and a main bolster supported adjacent its ends in the openings in the longitudinal bolsters the said main and longitudinal bolsters having interlocking connection with their support.

In testimony whereof, we have signed this specification in the presence of two subscribing witnesses.

JACOB C. LARSEN.
GEORGE T. JOHNSON.
